CLAIM

The ornamental design for an accessory device charger, as shown and described.

DESCRIPTION

FIG. 1 is a perspective view of an accessory device charger; FIG. 2 is a front elevation view thereof; FIG. 3 is a rear elevation view thereof; FIG. 4 is a left elevation view thereof; FIG. 5 is a right elevation view thereof; FIG. 6 is a top plan view thereof; and, FIG. 7 is a bottom plan view thereof.

The broken lines in the drawings depict portions of the accessory device charger that form no part of the claimed design.
